By W. O. T. Filman Attorney

UNITED STATES PATENT OFFICE

2,607,423

USE OF A FLEXIBLE SLEEVE IN THE
CEMENTATION OF BOREHOLESAlexander B. Hildebrandt, Tulsa, Okla., assignor
to Standard Oil Development Company, a cor-
poration of Delaware

Application September 17, 1947, Serial No. 774,649

1 Claim. (Cl. 166—1)

1

The present invention is concerned with an improved process for preparing bore holes for the production of oil. The invention is more particularly concerned with apparatus for securing an improved method for cementing casing in a bore hole. In accordance with the present invention, a flexible sleeve or skirt is attached to the bottom of the casing. This sleeve is adapted to expand against the bore hole wall as the sleeve is inflated with cement.

The general technique for the recovery of crude oil from oil-producing subterranean sands is well known. Generally, the process comprises drilling a bore hole or well through non-producing subterranean areas to oil-producing areas which generally comprise oil-producing sands. After the desired oil-producing area is reached, it is the usual practice to cement the area between the well casing and the bore hole wall. This procedure is followed in order to prevent the flow of undesirable fluids into the oil-producing sand area. The usual procedure is to introduce the required volume of cement as a slug in the drilling mud and to circulate the drilling mud. The cement passes downwardly within the casing and upwardly between the casing and the bore hole wall to the desired area, at which time circulation is discontinued.

In this operation it is very difficult to secure a satisfactory cementation of the desired area. For example, the drilling mud apparently has an adverse effect upon the cement either prior to or during the setting period. One result of this is that the cement seems to form channels through which undesirable fluids may flow into the oil-producing area, which fluids impair the efficiency and production of the well. Another problem encountered is that it is very difficult to secure a tight seal of cement against the bore hole wall.

I have now discovered a procedure and apparatus which is particularly adapted and directed toward overcoming these problems heretofore encountered. My apparatus comprises a flexible, expandable sleeve or skirt device which is attached to the lower end of the casing. In accordance with my process I force the cement into this sleeve or skirt device and cause the device to progressively expand against the wall of the bore hole. During the setting period the cement is not in direct contact with the drilling mud, thus assuring a better cementation result.

My process and device may be readily understood by reference to the drawings illustrating one embodiment of the same. Figure 1 illustrates the typical bore hole into which is disposed a casing containing a conventional shoe. Figure 1

2

also illustrates my sleeve or skirt device which is attached to the lower end of the casing. Figure 2 is a top cross-sectional view of the casing taken across the line A—A'. Figure 3 illustrates the position of the skirt during the cementing operation.

Referring specifically to Figure 1, 10 designates the bore hole into which is disposed casing 11. A conventional shoe device 12 is attached to the bottom of casing 11. In accordance with my invention, I attach to the outer surface of casing 11 a skirt arrangement 13. Also in accordance with my process, I employ at least one closed breakable opening in the lower area of casing 11. Usually a series of closed breakable openings are desirable in the lower area of casing 11. Figure 1 illustrates the arrangement of my device prior to the commencement of the cementation process.

Figure 2 illustrates the lapping over or folding of my expandable skirt device. Figure 3, as heretofore pointed out, illustrates the operation of my device during the cementation process. In accordance with my process at the surface I insert a suitable plug 14 into the casing. In the area 20 above the plug I place the desired amount of cement which I intend to use in the cementation process. I insert another plug 15 on top of the cement and fill the area above plug 15 with drilling mud, and circulate the mud and the cement within the casing to the bottom of the drill hole as shown in Figure 3. As the plug 14 approaches the bottom of the casing, drilling mud within the casing is forced out of the casing through shoe 12 up into the area between the casing and the bore hole wall. When plug 14 reaches the bottom 30 of the shoe it seals off further flow of material through the shoe. Thus, the pressure within the casing is increased causing breakage of closed breakable ports 25. It is to be understood that these ports may be grooved or otherwise treated 35 so as to make the tensile strength of them substantially less than the strength of the casing wall.

Upon breakage of ports 25 the sleeve or skirt arrangement 13 is caused to expand outwardly 40 against the bore hole wall. My skirt arrangement is so designed that initially the lowest portion of the skirt will be forced against the bore hole wall and that an upward thrust against the drilling mud fluid will be exerted as the skirt progressively 45 and upwardly expands against the bore hole wall. A special adaptation of my process is to employ breakable straps 17, 18, 19 and 20. It is to be understood that the number of these straps may be varied considerably, depending upon the height 50 of the skirt and the distance between the casing 55

and the bore hole wall. In accordance with the preferred working of my device, straps 17, 18, 19 and 20 are broken in sequence by the force of the cement entering within the skirt. These straps are so designed that no cement will pass upwardly within the flexible sleeve until the strap is broken. A particularly desirable feature is to employ hinged straps or latches which can be flopped outwardly from the lower edge of the strap as the cement in the skirt rises. As the lower half of the strap is moved outwardly, the strap around the skirt holding it securely to the outer wall of the casing will be released.

My invention generally is concerned with the use of a sealed area in the bottom of the bore hole into which cement is forced and into which drilling mud cannot seep during the cement setting period. It is also generally concerned with the use of this sealed area so as to cause the cement to exert a tight seal against the bore hole wall rather than to take the path of least resistance and flow upwardly into the area of the drilling mud. By operating in this manner, cavitation or channeling of the cement is prevented and a tight seal is secured in the area between the casing and the bore hole wall.

Although any suitable device may be used in order to carry out my process, the preferred method is to employ an expandable skirt device which is attached to the lower part of the casing. The expandable device is caused to expand by forcing cement through suitable openings or ports in the casing into the area between the inner surface of the expandable device and the outer surface of the casing. A preferred device comprises a lapped unit, the lappings of which are sufficient to expand throughout the area it is desired to cement. The length of the skirt may vary appreciably. It may range, for example, from 50 to 100 or even as high as 1000 feet. Although it is desired to force the cement into the expandable device at the bottom of the device, it is to be un-

derstood that under certain conditions, particularly when the device is quite long, other points of entry for the cement may be provided for. Furthermore, although it is preferred that the expandable device comprise a suitable metallic material, it is to be also understood that other materials such as plastic, cloth, or various fabrics may also be utilized.

The process of my invention is not to be limited by any theory as to mode of operation, but only in and by the following claim in which it is desired to claim all novelty insofar as the prior art permits.

What is claimed is:

Improved apparatus for cementing a casing in a well bore comprising a casing section having at least one port through the wall thereof, a breakable seal closing said port, an expandable flexible skirt surrounding the exterior of said casing section over an appreciable length thereof above said port, the lower end of said skirt terminating below said port and adjacent thereto, and a plurality of separate straps encircling said skirt in spaced relation along the length thereof and releasably holding said skirt tightly against said casing section, said straps constituting the sole means supporting said skirt on said casing section.
